POWER JACK,

APPLICATION FILED DEC. 9, 1918.

Patented Nov. 23, 1920.

2 SHEETS—SHEET 2.

UNITED STATES PATENT OFFICE.

GEORGE R. WRIGHT, OF FORT WORTH, TEXAS.

POWER-JACK.

1,359,644.

Specification of Letters Patent. Patented Nov. 23, 1920.

Application filed December 9, 1918. Serial No. 265,938.

To all whom it may concern:

Be it known that I, GEORGE R. WRIGHT, a citizen of the United States, residing at Fort Worth, in the county of Tarrant and 5 State of Texas, have invented a new and useful Power-Jack, of which the following is a specification.

This invention relates to power jacks, one of its objects being to provide a walking beam structure having a novel arrangement of weighted pendulums combined therewith whereby momentum set up by the oscillation of the walking beam can be utilized for increasing the efficiency of the mechanism as 10 15 a pump operating means, in the same manner as the efficiency of any drive mechanism is increased by the use of a fly wheel.

A further object is to provide weighted pendulums so connected to the driven elements as to act directly upon them during the operation of the mechanism, the use of the pendulums permitting a considerable reduction in the power required to operate a pump.

With the foregoing and other objects in view the invention consists of certain novel details of construction and combinations of parts which will be hereinafter more fully described and pointed out in the claims, it 20 25 30 being understood that various changes may be made in the construction and arrangement of the parts without departing from the spirit or sacrificing any of the advantages of the invention as set forth in the 35 appended claims.

In the accompanying drawings the preferred form of the invention has been shown.

In said drawings—

Figure 1 is a front elevation of the jack. 40 Fig. 2 is a plan view thereof.

Fig. 3 is a view showing in full and dotted lines two positions to which the parts will move during the operation of the mechanism.

Referring to the figures by characters of reference, 1 designates a stand or supporting frame having a bearing 2 for a centrally supported walking beam 3. An operating rod 4 is pivotally connected to one arm of 45 50 the walking beam and may be driven by any suitable mechanism so as to move the walking beam at a predetermined number of strokes per minute.

Pivotally connected to the ends of the

walking beam are pendulums 5 each including a weight 6 and journaled within the walking beam or upon one side thereof at points 7 equidistant from the bearing of the walking beam, are oppositely disposed bell crank levers 8 of the same size and 60 the lower arms of which are extended toward each other. The free ends of these lower arms are pivotally connected as at 9 to the upper ends of the pump rods 10. The upper ends of the upper arms of the 65 levers 8 are pivotally connected, as at 11, to a link 12. They are also pivotally attached to connecting rods 13 which extend downwardly past the walking beam and are pivotally connected, at 14, to the pendulums. 70

When the walking beam is oscillated by the application of power thereto through the reciprocating rod 4, the pump rods 10 will be given a reciprocating movement as ordinarily. As the oscillation of the beam continues, however, the pendulums will begin to swing until the relative movement thereof will be transmitted, through the rods 13 and levers 8 to the rods, thereby to increase the movement of said rods 10. In other 80 words, when the walking beam travels from one limit of its movement, indicated by dotted lines in Fig. 3, the pendulums will maintain their positions relative to the beam and the rods 10 will be shifted as ordinarily until the beam reaches the other limit of its movement where it is brought to an abrupt stop. This will cause the two pendulums to be impelled to the positions shown by full lines in Fig. 3 with the result that the bell 85 crank levers will impart further movement to the pump rods in the direction in which they had been moving. At the same time the pendulum on the lowermost arm of the beam 3 having been swung inwardly toward 90 the center of the beam and the other pendulum having been swung outwardly, the upper arm will overbalance the lower arm so that the power required to return the beam to its other extreme position will be 95 reduced.

What is claimed is:—

1. The combination with a walking beam and means for oscillating the same, of a pendulum hung from each end of the beam, 105 oppositely disposed levers movable with the beam and equidistant from the bearing thereof, a link connection between the levers,

and rods connecting said levers and the pendulums.

2. The combination with a walking beam, and means for oscillating the same, of pendulums hung from the ends of the beam, 5 weights thereon, oppositely disposed bell crank levers upon the walking beam, a link connecting the upper arms of said levers, and rods connecting the upper arms 10 of said levers to the pendulums at points

below the beam, and pump rods connected to the lower arms of the respective levers.

In testimony that I claim the foregoing as my own, I have hereto affixed my signature in the presence of two witnesses.

GEO. R. WRIGHT.
